CLAIM

The ornamental design for a paint shield for electrical outlet, as shown and described.

DESCRIPTION

FIG. 1 is a pictorial view of the paint shield for electrical outlet showing my new design wherein the front, bottom and left side views are visible.

FIG. 2, is a top view thereof, the bottom view being identical.

FIG. 3 is a right side elevation thereof, the left side elevation being identical.

FIG. 4 is a back view thereof.
